UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

FIXTURE CHAIN.

Application filed June 5, 1919. Serial No. 301,948.

To all whom it may concern:

Be it known that I, REUBEN B. BENJAMIN, a citizen of the United States, residing at Chicago, in the county of Cook and State 5 of Illinois, have invented new and useful Improvements in Fixture Chains, of which the following is a full, clear, concise, and exact description, reference being had to the accompanying drawing, forming a part of 10 this specification.

This invention relates to fixture chains of the type in which the chain is formed of a plurality of open links separably connected to permit of ready adjustment of the 15 length of the chain, and through which an electric conductor may be passed to furnish current for the fixture suspended by the chain.

The object of this invention is the production of a fixture chain of the character 20 mentioned which will be so constructed as to afford means for positively locking the links against spreading at the openings therein. A further object is the production 25 of a chain characterized as above mentioned in which the links, though of light construction, will be possessed of great strength and rigidity, and in which a construction will be produced which is of neat and pleasing 30 design and economical of manufacture.

A still further object is the production of a fixture chain in which the links will be so 35 designed as to insure vertical disposition or hanging thereof notwithstanding distortion or non-uniformity of the links due to inaccuracy in manufacture.

With these objects in view, the invention 40 consists in the combinations and arrangements of parts hereinafter described and claimed.

The accompanying drawings forming a part of this specification, show one embodiment of my invention, and in said drawings

Fig. 1 is a side elevation of a fragment of 45 chain embodying the invention;

Fig. 2 is a perspective view illustrating more clearly the inter-locking relation between neighboring links;

Fig. 3 is a section taken on substantially line 3—3 of Fig. 1, the electric conductor being omitted;

Fig. 4 is a fragmentary perspective view of the lower portion of one of the links; and

Fig. 5 is a sectional view illustrating the manner of removing the links.

The preferred form of construction, as illustrated in the drawings, comprises a chain consisting of a plurality of similar links 10 which inter-engage with each other. Each link is formed of a strip of sheet metal 60 of uniform thickness throughout and of uniform width from end to end, said strip being bent into oval or loop form. Each link is also so formed that the sides thereof have convex outer surfaces 11 and concave inner 65 surfaces 12, the radius of curvature being smallest midway between the ends of the link and gradually increasing toward said ends. Viewed in the plane of the link, the projected width of each link varies gradually 70 from a maximum at the points where it engages its neighbors to a minimum at points midway between its engaging ends.

The ends 13 of each link are flat and are provided with centrally positioned openings 75 14 to accommodate the electric conductor 15 which is thus adapted to pass centrally through the chain being, in a sense, enclosed thereby. In order to guard against abrasion or cutting of the conductor, each opening 14 is surrounded by a rounded or flaring flange 16 which, as will be apparent, positively precludes the possibility of cutting or otherwise injuring the insulation of the conductor.

In order to allow for engagement or disengagement of the links, so as to permit of readily varying the length of the chain, each link is formed at one end with a centrally positioned transversely extending opening 17, the same being of a width slightly greater than the thickness of the metal forming the links so as to permit of the ready passage of a link therethrough in the manner clearly illustrated in Fig. 5. With this arrangement, adding or removing of links may be

readily and easily accomplished through but slight springing or spreading of the link to widen the opening therein so as to allow for the passage of the adjoining link.

5 Formed in each link at opposite sides of the opening 17 therein, are recesses or notches 18, there being two recesses at each side of the opening, provided at opposite sides of the link. Said recesses open laterally or in directions substantially parallel with the plane of the opening in each link, so that, with the links in operative relation with each other, the inwardly turned edges of the sides of the upper neighboring link will engage the 15 four recesses of the lower link and thus serve to positively lock the latter against spreading at the opening therein. Accidental opening or rupture of the chain is thus rendered practically impossible. This engagement of the neighboring link with the recesses of the recessed link is best seen in Figs. 2 and 3.

By reason of the increased curvature of the sides of each link toward the center of 25 the link, it will be seen that the closer to the center the recesses of each link engage the inwardly turned edges of the sides of the neighboring link, the more positive and efficient is the locking effect of said edges, 30 and to secure engagement of said notches with said edges at points removed from the end of the link, that is, toward the center of the latter, the lower end of each link is provided with upwardly offset or beaded portions 19 against which the upper end of 35 the recessed link engages and whereby the engaging ends of the links are held apart as will be readily understood.

At the same time the two offset portions 40 19 formed in each center provide an arrangement wherein adjacent links engage each other at only two points, permitting of the lower link rocking thereon to assume, by gravity, a substantially vertical position. 45 This is of particular advantage in that it compensates for distortion and inaccuracies due to faulty manufacture and obviates the possibility of a twisted or skewed chain such as might otherwise result in the case of distorted links which had their ends engaging 50 each other in such a manner as to bar relative tilting or rocking of the links.

The curved formation of the sides of each link lends strength and rigidity to a light 55 and otherwise weak construction. Such formation insures against distortion of the link under severe strain, and because of the saving in material effected, through the use of light material, provides a chain which may 60 be marketed at a low cost. The curvature of the links also produces a chain of neat, finished and pleasing design. By curving the links so that the convexity thereof is outward, rounded external surfaces are pro-

duced devoid of sharp edges which cut, 65 scratch or otherwise mar any surface against which the chain might strike during use.

Having thus described my invention, what I claim as new and desire to secure by Letters Patent is:

70 1. A separable-link fixture chain comprising inter-engaging links, each having an opening to permit of the passage of another link, said opening in each link being positioned at the point of engagement between the link and a neighboring link; and recesses in the outer edges of each link at opposite sides of said opening therein, said recesses being engaged by adjacent portions of the neighboring link.

75 2. A separable-link fixture chain comprising inter-engaging links, each having an opening to permit of the passage of another link, said opening in each link being positioned at the point of engagement between the link and a neighboring link; and recesses in the outer edges of each link at opposite sides of said opening therein and facing in directions substantially parallel with the plane of said opening, said recesses being engaged by adjacent portions of the neighboring link.

80 3. A separable-link fixture chain which comprises inter-engaging links, each having an opening to permit of the passage of another link, said opening in each link being positioned at the point of engagement between the link and a neighboring link; laterally opening recesses in the outer edges of each link at opposite sides of said opening therein; and inwardly turned portions on the neighboring link engaging said recesses.

85 4. A separable link fixture chain comprising inter-engaging split links, said links being formed of bands of sheet material with portions of their edges inwardly turned, the split portion of each link being positioned at the point of engagement with a neighboring link, and recesses being formed at the outer edges of each link at opposite sides of the split portion, said recesses being engaged by adjacent inwardly turned edges of the neighboring link, whereby spreading of the split links is prevented.

90 5. A separable link fixture chain comprising inter-engaging links formed of bands of sheet material, the portion of each link positioned at the point of engagement with a neighboring link being substantially flattened, and embossed points of support formed at the flattened portion for rocking support of the neighboring link in self-aligning position with the chain.

95 6. A separable link fixture chain comprising inter-engaging split links, the split portion of each link being positioned at the point of engagement with a neighboring

link and being substantially flattened, other portions of each link being inturned at the edges forming an outwardly convex surface, recesses formed at the outer edges of each

- 5 link at opposite sides of the split portion, and embossed points of support formed at the flattened portion for rocking support of the neighboring link in self-aligned po-

sition with the chain and with said recesses in engagement with adjacent inturned edges 10 of the neighboring link whereby the split link is locked against spreading.

In witness whereof, I have hereunto subscribed my name.

REUBEN B. BENJAMIN.
